UNITED STATES PATENT OFFICE.

WILLIAM HENRY LEGATE, OF HARTFORD, CONNECTICUT.

INTERNAL-COMBUSTION ENGINE.

Application filed January 24, 1920. Serial No. 353,669.

To all whom it may concern:

Be it known that I, WILLIAM H. LEGATE, a citizen of the United States, residing in Hartford, in the county of Hartford and 5 State of Connecticut, have invented a new and Improved Internal-Combustion Engine, of which the following is a specification.

My invention relates to the type of engines above named, and an object of my invention, among others, is to provide an engine of this type that shall have means for reducing or practically eliminating the collection of carbon and other impurities on the valves and on the walls of the combustion chamber.

One form of device embodying my invention and in the construction and use of which the objects herein set out, as well as others, may be attained, is illustrated in 20 the accompanying drawings, in which—

Figure 1 is a perspective view of a piston commonly used in internal combustion engines and embodying my invention.

Figure 2 is a view in section through a 25 portion of the cylinder and piston of an internal combustion engine, said piston embodying my invention.

It is a well known fact that carbon and other impurities collect to an objectionable 30 extent in most of the internal combustion engines in use at the present time, thereby preventing the most efficient results from being obtained in their operation, this deposit of carbon and other impurities creating a medium within the combustion chamber for taking and retaining heat sufficient to cause premature explosions in a manner and at such times as to greatly reduce the efficiency of the engine under these conditions. My invention provides a structure 35 wherein this deposit of carbon and other impurities is greatly lessened, and in fact, practically eliminated.

The piston of an internal combustion engine is very susceptible to the deposit of carbon hereinbefore referred to, and I have, therefore, shown in the drawings herein my invention as especially applied to such piston, in such drawings the numeral 5 indicating a fragment of a cylinder within which 40 a piston 6 is mounted to reciprocate in the ordinary manner, said cylinder comprising a combustion chamber 7.

In carrying my invention into effect I form an opening 8 through the piston head 9, this opening being of a size closely ap-

proaching the size of the opening within the piston, and within this opening 8 I place a dome or lining preferably constructed of a metal to which carbon deposits are little 60 likely to adhere. This opening 8 is formed with a recessed mouth 10 into which the dome, hereinabove referred to, is forced under great pressure, the parts being so formed that after such pressure has been applied the dome will be retained securely in place. In the preferred form of the structure the recessed mouth is undercut to receive the edge of the dome which is forced tightly into place therein. This provides a 70 structure that is very simple in its construction and that completely forms the end or bottom wall of the opening within the piston. The temperature within the chamber in the piston being much less than that 75 in the combustion chamber 7 and the dome being exposed to the full effects of the fluid contents within the chamber in the piston, said contents are made use of to reduce the temperature of the dome and thereby maintain that wall of the combustion chamber 80 formed by the piston head at a much lower temperature than would otherwise be obtained.

A very effective structure with the use of 85 which the results contemplated may be obtained comprises a dome or lining 11 containing a chamber 12, in the preferred form of construction, this dome being composed of two plates having facing convex surfaces 90 constituting said chamber 12. I prefer that these plates shall be concavo-convex in shape and they may be secured together at the peripheral edge thereof in any suitable manner and they may be forced and held within 95 the recess 10 in the manner hereinabove described, the outer plate being shaped in the general form of the outer end of the piston to provide a smooth surface thereon.

While my invention is not confined to any 100 specific metal having the properties for resisting the deposit of carbon herein described, yet I have found that "German silver" will produce extremely satisfactory results.

I have illustrated and described my invention as applied to that wall of the combustion chamber formed by the end of the piston but my invention contemplates a structure in which other parts of the wall of the combustion chamber may receive my improved lining.

In accordance with the provisions of the patent statutes, I have described the principles of operation of my invention, together with the device which I now consider to represent the best embodiment thereof; but I desire to have it understood that the device shown is only illustrative, and that the invention may be carried out by other means.

I claim—

- 10 1. The combination in an internal combustion engine having a piston chamber therein with a recessed wall, of a lining originally larger in area than said recess but forced thereinto to secure it therein.
- 15 2. The combination in an internal combustion engine having a combustion chamber therein with a recessed wall, of a lining comprising two pieces of material formed with a space between them and originally 20 larger than said recess, but forced thereinto to secure said lining in place.
- 25 3. The combination in an internal combustion engine having a combustion chamber therein with a recessed wall, of a lining secured in said recess and comprising two

pieces of material formed to provide a chamber between them.

4. In combination in an internal combustion engine having a combustion chamber therein, a member reciprocatingly mounted in said chamber and forming a movable wall thereof, which wall has an opening formed therethrough with a recessed mouth, and a lining secured in said recess. 30

5. The combination in an internal combustion engine having a combustion chamber therein, of a piston mounted to reciprocate in said chamber, said piston having a recessed opening through its end, and a lining comprising two pieces of material 35 curved to form a chamber between them, said lining being secured in said recess. 40

6. The process of forming a piston for an engine that consists in providing a recess in the end of the piston, forming a piece of material having an area slightly larger than said recess, and then forcing said material into said recess to form a lining. 45

WILLIAM HENRY LEGATE.
